UNITED STATES PATENT OFFICE

152,553

DESIGN FOR A BOTTLE OR SIMILAR CONTAINER

Malcolm A. MacLean, West Bridgewater, Mass., assignor to Albert H. Clime, North Abington, Mass.

Application November 26, 1947, Serial No. 142,808

Term of patent 14 years

(Cl. D58—6)

To all whom it may concern:

Be it known that I, Malcolm A. MacLean, a citizen of the United States, residing at West Bridgewater, in the county of Plymouth and Commonwealth of Massachusetts, have invented a new, original, and ornamental Design for a Bottle or Similar Container, of which the following is a specification, reference being had to the accompanying drawing, forming part thereof.

Fig. 1 is a plan view of a bottle or similar container showing my new design;

Fig. 2 is a front elevation of the bottle or similar container;

Fig. 3 is an end elevation of the bottle or similar container; and

Fig. 4 is a bottom view of the bottle or similar container.

I claim:

The ornamental design for a bottle or similar container, as shown.

MALCOLM A. MACLEAN.
